UNITED STATES PATENT OFFICE.

SAMUEL DOBRIK, OF BROOKLYN, NEW YORK.

DENTAL MOLDING PLATE.

Application filed June 8, 1925. Serial No. 35,526.

My invention relates to a new and improved molding plate construction to be used for dental purposes.

One of the objects of my invention is to provide a molding plate which shall be sanitary, which can be readily adapted for the individual mouth whose teeth are to be restored and which can be readily shaped by the dentist to accommodate its use to the mouth of the patient who is being treated. Such a plate may be made of any material which can be easily cut, as, for example, a waxy material.

Another object of my invention is to devise an article of this character which can be readily manipulated and to which a metal holding handle can be affixed in a secure manner.

Another and important object of my invention is to provide a fundamental form or type of plate which can be used for taking impressions of the full upper jaw or of the full lower jaw, upon being suitably shaped by the dentist for the purpose for which it is intended.

Other objects of my invention will be set forth in the following description and drawings which illustrate a preferred embodiment thereof, it being understood that the above general statement of the objects of my invention is intended to generally illustrate the same and not to limit it in any manner.

Fig. 1 is a perspective view of a molding plate to be used for molding the upper jaw.

Fig. 2 is a perspective view of the holding member to be used in combination with the plate shown in Fig. 1.

Fig. 3 is an inverted plan view showing the holding handle applied to the molding plate and the holding member therefor.

Fig. 4 is the same as Fig. 1 but showing a portion of the molding plate cut away so as to enable the device to be used with a relatively shallow jaw.

Fig. 5 is the same as Fig. 4 but showing the central portion of the holding plate cut away so as to enable the device to be used as a molding plate for the lower jaw, this figure also showing a part of the plate cut away so as to enable the device to be used for a relatively shallow jaw.

Fig. 6 is a perspective view showing the device shown in Fig. 5 in the inverted position and with fewer of the corrugations cut away.

Fig. 7 is a perspective view of a molding

plate to be used as a partial tray for the side portion of the upper or lower jaw.

Fig. 8 is a perspective view of a holding member to be used in combination with the plate shown in Fig. 7.

Fig. 9 is a top view showing the holding handle and holding member applied to the device shown in Fig. 7.

Fig. 10 is a section on the line 10—10 of Fig. 9.

Hitherto in taking impressions for dental purposes, for the purpose of making bridge work and for other dental work where restoration of teeth is necessary, it has been customary to use a hollow metal molding plate in which the impression material was placed, so that a proper impression could be taken. Plates of this kind were not sanitary in that they were used again and again and in addition, since the mouths of various patients are more or less shallow, a dental plate made of metal was necessarily adapted for the deepest type of mouth so that it proved uncomfortable for patients having relatively shallow mouths and this also interfered with the accuracy of the work taken. According to my invention, the molding plate is made of any material which can be readily cut or shaped by the dentist.

As shown in Fig. 1, the fundamental type of molding plate, which can be readily shaped by the dentist for the various purposes for which it is used, consists of a plate having a peripheral portion 1, a central or palatal portion 2 and a depending wall 3 having a series of corrugated portions separated by corrugation lines 4. The peripheral portion 1 is provided with relatively raised extensions 5, 6 and 7 separated from the main peripheral portion 1 by slots so that the corresponding tongues of the holding handle can be inserted between the peripheral portion 1 and the said raised portions 5, 6 and 7.

To enable the molding plate to be suitably held by the dentist, a holding member 8 is provided and this holding member 8 is also provided with relatively raised side shoulders 9 and 10.

This holding member 8 is provided with depending walls 11 and 12 so that it can be fitted upon the molding plate 1.

A handle H is provided with tongues 14, 15 and 16 so that when the handle H is thrust into position as shown in Fig. 3, the tongues 14, 15 and 16 engage the molding

plate 1 and the holding member 8, as shown in Fig. 3. The central tongue 16 passes underneath the central shoulder 5 of the molding plate 1 and the end tongues 14 and 5 15 pass underneath the shoulders 6 and 9 on one side and the shoulders 10 and 7 on the other side, so that a firm frictional fit is secured which could not be secured with the same advantageous effect if the holding member 8 were omitted.

10 The molding plate shown in Fig. 1 is adapted for taking an impression of the entire upper jaw of the deepest type.

15 If the upper jaw of the mouth of the patient is more shallow than the deepest type before mentioned, then more or less of the corrugations of the side walls 3 can be cut away. I have not illustrated in detail 20 the appearance of the fundamental type of plate shown in Fig. 1, as the corrugated portions of the depending walls 3 are gradually cut away, because this is unnecessary 25 for a clear understanding of my invention because it can be readily appreciated that the skilled dentist will cut away more or less of these corrugated portions, depending upon the mouth of the patient who is being treated.

30 In order to adapt this plate for taking an impression of the entire lower jaw, the palate portion 2 can be cut away so as to make a device of the type shown in Figs. 5 and 6, the type shown in Fig. 6 having less of the side walls cut away so that it is 35 intended for a deeper type of jaw than the device shown in Fig. 5.

30 If it is desired to take a small impression of only a part of one of the jaws, then the device shown in Figs. 7-10 inclusive can be 40 employed. The molding plate 17 shown in Fig. 7 has a single raised shoulder 18 and this is embraced by the holding plate 19 shown in Fig. 8, the said holding plate 19 having a raised shoulder 20.

45 A holding handle H' having a single tongue 21 is employed in connection with the small plate shown in Fig. 7.

50 As shown in Fig. 10, the tongue 21 is curved so that it engages the underside of the shoulder 18 and also engages the upper side of the shoulder 20, thus providing for a firm frictional engagement where only a single holding tongue is used.

The purpose of using the holding member

8 is to have the handle fit tightly and secure 55 a firm frictional hold upon the molding plate. If the tongues 14, 15 and 16 of the handle H were directly inserted below the extensions or shoulders 5, 6 and 7, then the said handle H and molding plate 1 might 60 have a certain relative movement because the material of which the molding plate is made is not stiff and rigid, as if metal were used for this purpose. However, when the holding plate 8 is applied to the molding 65 plate 1, the respective ends of the tongues 14 and 15 are firmly forced against the upper surface of the holding plate 8 when the tongues are inserted into bridge-like extensions 6 and 7 so that a firm hold is secured. 70 The holding plate 19 also enables the handle H' to firmly hold the small molding plate 17.

75 I have shown a preferred embodiment of my invention, but it is clear that numerous changes and omissions could be made without departing from its spirit.

80 Experience has shown that the corrugations previously described in the said molding plates aid a dentist materially in enabling him to secure a more accurate impression, because these corrugations enable the plate to hold the impression material in one solid mass so that the impression material does not break into parts, which frequently occurs when the plate is not properly 85 shaped.

85 I claim:—

90 1. In combination, a dental molding plate having bridge-like extensions at the front thereof and at the sides thereof, and a holding plate adapted to fit over said molding plate and having bridge-like extensions corresponding to the before mentioned extensions upon the sides of the said molding plate.

95 2. In combination with the device specified in claim 1, a handle having tongues adapted to engage the said molding plate under the said extensions thereof, the said tongues being adapted to firmly bear against the exterior of the said holding plate.

100 3. A molding plate having a bridge-like extension, a holding plate adapted to fit over the said molding plate and having a second bridge-like extension corresponding to the first bridge-like extension.

105 In testimony whereof I affix my signature.

SAMUEL DOBRIK.
